Charles P. Ide, Sharon, Pa.

Application August 12, 1953, Serial No. 26,433

Term of patent 14 years

(Cl. D45—17)

Fig. 2.

Fig. 1.

To all whom it may concern:

Be it known that I, Charles P. Ide, a citizen of the United States, and a resident of Sharon, county of Mercer, State of Pennsylvania, have invented a new, original, and ornamental Design for a Pendant or Similar Article, of which the following is a specification, reference being had to the accompanying drawings, forming a part thereof, wherein:

Figure 1 is a perspective view of the pendant or similar article showing my new design thereof; and

The dominant features of my design reside in those portions shown in full lines.

I claim:

The ornamental design for a pendant or similar article, as shown and described.
